UNITED STATES PATENT OFFICE.

HARRY AGLOW, OF NEW YORK, N. Y., ASSIGNOR TO THE NEW YORK LIGHTING FIXTURE MFG. CO., A CORPORATION OF NEW YORK.

DESIGN FOR A LIGHTING-FIXTURE BODY OR ARTICLE OF SIMILAR NATURE.

Application filed January 7, 1928. Serial No. 24,772. Term of patent 3½ years.

To all whom it may concern:

Be it known that I, HARRY AGLOW, a subject of the King of Great Britain, and a resident of New York, county of Bronx, and State of New York, have invented a new, original, and ornamental Design for a Lighting-Fixture Body or Article of Similar Nature, of which the following is a specification, reference being made to the accompanying drawing, forming a part hereof.

In the drawings:

Figure 1 is a side elevational view of the lighting fixture body or article of similar nature; and

Figure 2 is a diagrammatic outline view to indicate the contour of the article when viewed from below.

I claim:

The ornamental design for a lighting fixture body or article of similar nature substantially as shown.

HARRY AGLOW.
